SEWING MACHINE IN NECKTIE
CONSTRUCTION

Victor M. Newman, New York, N. Y.

Application February 10, 1949, Serial No. 75,595

29 Claims. (Cl. 112—174)

1

This invention relates to sewing apparatus and more particularly to a machine which is adapted to sew neckties.

Sewing machines having an elongated needle for stitching together the necktie lining and the edges of the necktie are known but their use has been associated with some disadvantages. For example, the machines are not well adapted to accommodate neckties which deviate from predetermined dimensions. In other words, if the machine is set up to sew neckties of a particular size, those which have been cut larger will produce distorted finished products which may be rejected as unusable. Another disadvantage has been frequent breakage of the needle in that its guiding path was not properly formed.

The sewing apparatus of the instant invention eliminates the above mentioned disadvantages. In addition, a more positive and reliable operation is secured in that there is less chance for interacting elements to become improperly engaged.

Another object of the instant invention is to produce such a sewing apparatus wherein the tie elements may be initially disposed in proper position which position will be substantially maintained until the sewing operation is completed. Thus, the operator may be substantially assured that the elements of the necktie will be properly sewn in the relationship which he considered desirable.

Another object of the instant invention is to provide a necktie sewing apparatus wherein the initial positioning of the fabric insures the accuracy of the fold for sewing its edges together and brings such edges properly together in position to be sewn by the travel therethrough of an elongated needle.

The apparatus of the instant invention is further designed so that it may sew neckties of differing dimensions and shapes. Thus, the lining and fabric supporting elements may be initially shifted into proper position for producing runs of varying necktie sizes.

Other advantages and objects such as the comparative simplicity of the apparatus will appear from the following detailed description and drawings.

In the drawings:

Fig. 1 is a planar, partly broken away view of the machine which comprises the instant invention.

Fig. 2 is a section along the lines 2—2 of Fig. 1.

Fig. 3 is a section along the lines 3—3 of Fig. 1.

Fig. 4 is a section along the lines 4—4 of Fig. 1.

2

Fig. 5 is an end elevational view of the machine in the closed or sewing position.

Fig. 6 is a fragmentary view illustrating the position of the tie elements on the machine before it is folded to the closed or sewing position.

Fig. 7 is an enlarged section substantially along the lines 7—7 of Fig. 6.

Fig. 8 is a top plan view of a modified embodiment partly broken away.

Fig. 9 is a fragmentary view of the needle impaling mechanism of Fig. 8.

Fig. 10 is a view along the lines 10—10 of Fig. 8.

Fig. 11 is a top plan view illustrating a further modified embodiment.

Fig. 12 is a view along the lines 12—12 of Fig. 11.

Fig. 13 is a third embodiment.

Figs. 1 to 7 disclose a simplified form of the apparatus and comprise a pair of platforms or blocks 15 and 16 which are formed with ears 17 wherein are disposed pivots 18 so that the platforms 15 and 16 are pivotally connected. As noted in Figs. 4 and 5, platform 15 may be stationary and supported on legs 20 and 21.

Maintained on platform 15 is the corrugated strip 22 which preferably, but not necessarily, assumes the approximate form of the necktie lining which is to be sewn to the necktie. In this embodiment, the strip 22 has been illustrated as a single unit, but in actual practice it may be desirable to employ the split or adjustable form thereof illustrated in Fig. 8 et seq. Strip 22 engages the complementary strip of platform 16, in forming a predetermined needle guide path for sewing the necktie and in determining the nature disposition of the stitches. As illustrated in Fig. 2, the surface of strip 22 is formed from crest 23 and valleys 24. Each crest 23 has formed therein a recess 25 which extends substantially to the dotted line position of Fig. 2. Such recesses may be produced by filing each crest to the desired depth. Strip 22 may be shaped to comprise two somewhat trapezoidal end sections 26 and 27 and a connecting central elongated rectangular section 28. Sections 26 and 27 respectively accommodate the front and back portions of the necktie while section 28 represents the neckband portion. The axis of each end section 26 and 27 is arranged to be inclined to the axis of section 25, such inclinations of the end sections being toward each other. The strip 22 is formed with needle holes 30 in which the fabric impaling needles travel as will be hereinafter described.

Platform 16 is provided with a strip 35 which is complementary to the strip 22 of the platform

55

15. Strip 35 is formed with flattened crests 36 and narrowed valleys 37 which mate with the respective crests and valleys of strip 22 when the platform 16 is pivoted and overlie platform 15 in the position illustrated in Fig. 5. Strip 35 substantially duplicates the shape of strip 22. It is formed with a series of somewhat elongated recesses 38 in the crests thereof, the approximate depth being indicated by the dotted line of Fig. 3. Such recesses 38 may be similarly formed by filing away central portions of the crests 36. Fabric impaling needle holes are likewise formed through strip 35 so as to mate with such needle holes of strip 22.

As illustrated in Fig. 6, the necktie lining L is placed in position along strip 22 as is a longitudinal edge portion of the necktie fabric T. The opposing strip 35 receives only the opposite longitudinal edge portion of the necktie fabric T and no portion of the lining L. Means are then provided to press the layers of fabric into the valleys 24. Such means take the form of the pivoted rod structure 40 comprising a series of rods 41 rigidly supported by a shaft 42. Shaft 42 is pivotally maintained in bearing lugs 43 and 44 and is provided with a handhold member 5. Pivotal rotation of hand hold member 45 from the position shown in Fig. 1 brings the rods 41 into the position shown in Fig. 6 so that the rods push the fabric inwardly and into substantially snug fitting engagement with the crests 23 of strip 22. The rods 41 may be of varying lengths as illustrated so that they occupy the same relative outward position as the line of recesses 25. It may be here noted that both the necktie lining and necktie fabric are generally cut on the bias so that they may stretch in lengthwise direction. Such bias cut is of assistance in permitting any required stretch of the fabric in order that it may be properly seated in the recesses 24. However, and as will be evident, the rods 41 may be individually pressed down when in operative position so as to assure proper seating of the fabric on the strip 22. Platform 16 is also provided with a rod structure 50 which serves the same function as the rod structure 40. Thus, when pivoted inwardly, the rods 51 depress the necktie fabric so that it assumes the general surface shape of strip 35.

In order to commence the sewing of the necktie, the entire platform 16 is pivoted so that it overlies platform 15 and the strips 22 and 35 engage, the fabric being between them. However, it is considered desirable in the form of the invention shown, to impale the fabric prior to rotation of the platform 16 in order that the predetermined disposition of the fabric be not unduly disturbed or varied. Accordingly, means are provided to cause a series of needles 60, to penetrate the fabric at points inwardly of the recesses. Such needles will just barely penetrate the fabric layers and will be received in complementary needle holes of the opposite strip. An elongated plate 61 supports all of the fabric impaling needles 60 in perpendicular relationship. When the plate 61 is raised, the needles 60 rise accordingly in the needle holes 30 and upwardly in valleys 24 into the corresponding needle holes of the crests 36 of the strip 35. As illustrated in Figs. 4 and 5, the action of the plate 61 is controlled by a rod 62 which rides in the eccentric slot 63 of a disc 64. Disc 64 is provided with a shaft 65 to which is connected a handhold member 66. A downwardly depending bearing lug 67 supports the shaft 65. When handhold member 66 is rotated, the rod

62 will ride in slot 63 so as to cause the plate 61 and the needle 60 to be raised or lowered accordingly. The bearing lug 67 and disc 64 may be repeated at the other end of the machine as illustrated by the broken lines of Fig. 1 whereby the plate 61 will be properly supported at both ends.

Platform 16 is provided with a similar plate 70, handhold member 69 and disc 71 duplicating the fabric impaling needle arrangement of the platform 15 and serving the same function for the other edge of the necktie. When the necktie elements have been shaped into the position of the respective strips 22 and 35 by the rods 41, and after the impaling needles have been driven into the fabric, the platform 16 is pivotally actuated so that the edges 75 and 76 of the necktie T (Fig. 6) are caused to be superimposed and intermeshed. At this time, the recesses 25 are brought into staggered alignment with recesses 38 so as to form a guided path for the elongated needle which sews the tie together. Thus, in the form shown, the recesses 38, in cooperation with recesses 25, form a somewhat angular or slightly bent and substantially continuous path which guides the sewing needle adjacent the edges 75 and 76 which are disposed in inclined position relative to the platforms.

The elongated sewing needle 80 assumes conventional form, it being of a somewhat resilient steel so that it may travel a bent path and yet be sufficiently sturdy to be driven through such path while penetrating the fabric layers. The thread 81 which is placed through the eye of the needle 80 serves to produce the stitches. Means for actuating the needle 80 are known, in the industry, but in any event, the needle may be actuated manually by providing a handhold member on the rear end thereof. However, in the ordinary commercial form of the apparatus, the needle 80 will generally be actuated by mechanical driving equipment such as by the "Needle Driving Apparatus for Sewing Machines" described in an application being filed by me herewith, now Patent No. 2,522,582, dated September 19, 1950.

In order to discourage accidental displacement of the rods during rotation of the platform 16, and in any event, to enhance the function of such rods, spring 85 may be effectively connected to shaft 42 so as to urge the rods into clamping engagement with the fabric. Spring 86 serves a similar purpose for the rods of platform 16.

After the needle 80 has been reciprocated through the path formed by the aligned recesses, and the thread 81 has been sewn through the fabric layers, the sewing of the tie may be considered as effected. However, the disposition of the rods 41 and 51 prevents reverse pivoting or restoration of the platform 16 because the sewing thread is over such rods. Accordingly, means are provided to remove the rods while the platforms are in superimposed or engaged relationship. Bearing lugs 43 and 44 are formed so as to ride over pinion racks 90 and 91 respectively. Thus, referring to Fig. 4, a pinion wheel 92 is rotatably connected as by shaft 93 to lug 43. When the wheel 92 travels across rack 90, the lug 43 is moved accordingly and the rods 41 may be withdrawn from within the folds of the corrugated strips. Crank handle 94 actuates wheel 92 in effecting withdrawal of the rod structure 40. Crank handle 95 actuates the wheel 96 of the platform 16 so as to produce a corresponding withdrawal of the rod structure 50. It will be understood, therefore, that after sewing of the

tie has been effected, and prior to separation of the platforms, the crank handles 94 and 95 will be actuated so as to withdraw the rods laterally and out of the composite platform structure.

The rods having been withdrawn, the platform 16 will be returned to its position of horizontal alignment with platform 15 so that the sewn tie and lining may be removed.

In Figs. 8 to 10 is illustrated a preferred embodiment which permits shifting of the strip portions to accommodate different sizes of neckties. It is not considered desirable to shift the strips bodily because the relative dimensions and shapes of the tie portions change as the size changes. Accordingly, portion 26a of strip 22a is separated from strip 25a at the line 100. Portion 25a is separated from portion 27a at the line 101. Each strip section is therefore movable in relation to the remaining sections. Section 26a is formed with ears 102 having slots wherein are slidably maintained bolts 103. Platform 15a is formed with three slots 104 which are somewhat perpendicularly related to the slots of the ears 102. Accordingly, strip section 26a is not only capable of lateral adjustment in relation to platform or block 15a, but its capability of movement further includes a horizontal component whereby the section may be horizontally tilted in order to secure proper adjustment.

In the same manner, ears 105 of central strip section 25a cooperate with the traverse slots 106 in permitting lateral adjustment of the central strip section. Adjustment of section 27a is effected by means similar to that of section 26a.

It will be recognized that by virtue of the movability of the strip sections, the fabric impaling needles are necessarily shifted in relation to the strips so that the needle holes 111 might ordinarily be misaligned. Accordingly, the platforms are formed with elongated and widened slots 112 which accommodate movement of the needles commensurate with movement of the needle receiving holes by virtue of shifting of the strip sections. A modified form of impaling needle system is employed in that the impaling needles 115 are connected to enlarged holders 116 which are spring loaded in tubes 117, the spring 118 serving to depress the holder 116 in the tube 117 which is itself threadedly connected to the corrugated strip. Accordingly, the normal action of the needle 115 is to become withdrawn below the surface of the corrugated strip. Referring to Fig. 10, if the bolt 120 is loosened at the same time as the other bolts securing strip 27a to the platform, the strip may be suitably shifted laterally or inclined to the longitudinal axis of the supporting platform. The needle holding tubes 117 will likewise shift within the slots 112 of the platform.

Modified means are provided to actuate the needle holders 116 for the purpose of either impaling or releasing the tie fabric. Thus, the handhold member 125 is connected to a shaft 126 which rotates or oscillates the eccentric wheel 127. A depending plate 128 serves as a bearing for shaft 126 and is formed with two vertical slots 129 and 130. Pins 131 and 132 are arranged to ride in such slots and such pins are disposed on the top and bottom of the eccentric wheel 127. Integral with pins 131 and 132 is the elongated plate 133 which is arranged to serve as an abutment for the needle holders 116 so as to prevent their displacement from within the tubes 117.

When handhold member 125 is actuated so as to bring the higher portion of wheels 127 into an upward position, the pin 131 is raised as shown in Fig. 9 and the plate 133 is raised accordingly so that the needle holders 116 are forced upwardly against the action of the springs 118, and the needles 115 are then caused to impale the fabric seated on the corrugated strip. If the handhold member 125 is rotated another half turn, the pin 131 is permitted to descend so as to permit the holders 116 to be actuated upwardly by springs 118 so as to cause the needles to be withdrawn.

If desired, indicia lines 135 are formed on the platform surfaces so as to assist in the matched adjustments of the opposing strip sections. However, it is proposed that such strip sections may be adjusted in situ as a test sewing needle is being directed through the aligned recesses. In other words, after approximate and preliminary adjustment of the opposed strip sections has been effected, the platforms may be superimposed and a test elongated needle may be applied through the formed guide path. If end strip section 35a is not in proper alignment, its holding bolts may be loosened and the strip shifted until the elongated needle travels freely through the engaged strips. In order that the holding bolts may be actuated, their position on platform 16a is reversed in that the bolt heads appear on the underside. To permit rotation of the bolts 120 so as to loosen the strip sections to permit a required adjustment, the bolts are provided with nuts 136 which have reduced portions 137 of rectangular form and which enter the slots in the platform, such as slots 104a. Accordingly, when the bolt head is rotated, the nut 136 will remain stationary so as to effect loosening of the strips in relation to the supporting platform and their adjustment thereon.

The operation of the apparatus will be understood from the foregoing description of its components. It will be understood that inasmuch as the recesses occupy a predetermined position, variations in the width of the tie T cannot affect the size of the tie even if it is accidentally pre-cut to over-size dimensions. After the tie has been sewn in the manner heretofore described, it is turned inside out so as to be in its wearing position. If, then, the tie has been accidentally cut over-size or is in some other manner distorted as to width, such distortions or variations will occur on the inside of the tie so that the tie will always assume the same predetermined shape, as long as the tie fabric and lining are initially pre-set so as to cover the recesses in the corrugated strips. The presence of the pivots 18 practically assures the proper guiding path for the needle as predetermined because the platforms cannot become mismatched to any important degree. Furthermore, the pre-positioning of the tie elements is of importance in facilitating the operation of the device and in decreasing the number of rejects or discards due to improper initial feeding of the tie to the structure or in shifting thereof after having been pre-set. The controlled operating position of the platforms is further useful in forming an accordingly controlled needle guide path so that recesses are properly aligned and needle breakage is less frequent.

An important feature of the instant invention is the fact that when the tie fabric has been initially positioned on the strips as illustrated, 75 it is automatically in proper folding position.

and such folding is automatically accomplished when the platforms are pivoted to bring together the edges of the tie fabric.

In Figs. 11 and 12 is illustrated a further modified embodiment wherein the rod structures are substantially eliminated. Thus, shaft 150, which is pivotally supported in the bearings 151 and 152 has connected thereto three elongated bars, two of which are illustrated, viz 153 and 154. Bar 153 is adjustably connected to arms such as arms 155a which in turn are connected to the shaft 150. Bar 153 serves the top strip section 26b in holding down the lining and tie fabric edges while they are penetrated by the impaling needle in needle hole 111. Since strip section 26b is shiftable as was its counterpart in Fig. 8, bar 153 is likewise made shiftable in order that its needle holes 157 may be properly aligned with those of the strip 26b. The needles of strip 26b are actuated in the same manner as those of 26a heretofore described. Bar 154 is likewise connected to shaft 150 by arms 155 and 156 and serves strip section 27b.

Bar 154 is rendered adjustable by the provision of slots 158 and 159 in the connecting arms while further slots 160 and 161 are formed adjacent the respective ends of the bar 154. Nuts 162 and 163, when tightened, clamp the bar to the connecting arms, and when loosened, permit adjustment thereof so that the respective needle holes may become aligned. The nuts are disposed at the upper side of bar 154 so as not to rest upon strip 27b when the bar 154 is applied thereover. In actual practice, the bar 154 may be swung over strip section 27b and may then be adjusted until the respective needle holes are properly aligned. Of course, needle holes 157 may be made larger than shown or somewhat oval as were needle holes 112 in order to provide a tolerance of adjustment.

In the same manner, bar 165 serves strip section 35b and bar 166 serves strip section 35c. Referring to Fig. 12, the tie lining and fabric will first be placed upon the strip sections as illustrated in Fig. 6, and the bars 153, 154, 165, 166 et seq. will be swung thereover so as to hold the tie lining and fabric down. At this time, the needle actuating plates will be operated so as to cause the needles to rise and impale the lining and fabric in the proper position. Thereafter, the bars will be swung outwardly and the platforms or blocks will be pivoted around the pivot 169 so as to bring the parts into superimposed relationship illustrated by the broken lines of Fig. 12. This crimps the fabric edges and produces the needle guide path 170 which permits reciprocation of the elongated needle for sewing of the necktie. Spring 171 is provided to maintain bars 165, 166 et seq. in outwardly supported position when the platforms are superimposed as illustrated in Fig. 12.

In Fig. 13 is illustrated a third modification which may accommodate neckties of differing sizes without requiring shifting of the strip sections. Thus, strip 175 is formed as was strip 22 of Fig. 1 but with its top end section 176 provided with three rows or sets of recesses. The center row of recesses 177 is similar to the recesses of the first embodiment while recesses 178 and 179 are aligned on both sides thereof converging near the commencement of central strip section 180. All the strip sections, including lower strip section 181, are integral. The strip sections 180 and 181 are not provided with a plurality of recess lines because those sections

respectively represent the neckband and narrow end of the necktie and are accordingly not considered of importance. The front portion of the tie is the most important portion thereof and it is the size of such front portion that is accommodated by the plurality of recess rows. If a necktie having a narrow front portion is to be sewn, row 178 will be employed. These recesses will engage, of course, with the recesses 182 of the opposite strip as hereinabove described. On the contrary, a necktie having a wide front portion will employ the recesses 178 and 183. Selection of the desired rows of recesses is accomplished by shifting of the elongated sewing needle 80 as illustrated at the top of Fig. 13.

An advantage of avoiding shifting of the strip sections is the fact that the impaling needle holes 184 will always be in the same position so that the holding bars, not shown, need not be shifted.

In any of the foregoing embodiments, the impaling needle function is considered to be of importance because the tie and lining will be securely maintained in place during the folding process notwithstanding different weaves of fabric and other variable characteristics thereof. Further, in order that the force of the driven needle does not disturb the aligned or engaged strips, a lock such as latch 15a of Fig. 1 may serve to maintain the platforms properly superimposed during the sewing process.

One of the difficulties in the operation of previous necktie sewing machines has been the requirement of skilled labor. It was necessary in many cases to fold the tie accurately and apply the lining in such a way that the necktie elements were properly sewn through the action of the machine. In using the present invention, the operation is almost foolproof in that the elements need merely be laid down in position on the strips, the machine closed and the needle actuated. The strips themselves and the recesses formed therein dictate the position of the tie elements so that relatively unskilled labor is required therefor. If a tie lining has been cut oversize, it will nevertheless be sewn to the correct size as described above. It is further possible to utilize linings which have been cut slightly undersize by manually pulling the fabric transversely until the operator is certain that the edges have passed the rows of recesses. Only a slight extension is possible for this purpose, but otherwise unusable fabrics may often be usefully employed instead of being discarded.

What is claimed is:

1. Sewing mechanism comprising a pair of corrugated and complementary strips for crimping fabric, said strips being adapted to engage each other by their corrugations and being normally aligned in a horizontal plane so that the fabric may be deposited over both strips, and means to fold one strip over the other so as to fold the fabric therebetween while engaging the strips, the strips being respectively formed with recesses which become mutually aligned when the strips are engaged, the aligned recesses forming a needle path.

2. Sewing mechanism according to claim 1 and including a pair of platforms which are pivotally interconnected, said strips being supported on the respective faces of the platforms and disposed so as to become engaged when the platforms are relatively pivoted so as to be brought into substantial planar and superimposed contact with each other, said strips being spaced

from each other when normally horizontally aligned so that substantially only the edges of the fabric are crimped thereby.

3. Sewing mechanism comprising a pair of corrugated and complementary strips for crimping a lining and necktie combination, the corrugations of one strip being adapted to engage the corrugations of the other strip, a series of rods connected adjacent to each strip, each of said rods being adapted to fit into a corrugation of one of said strips, means for applying said rods to said strips so as to urge the lining and necktie fabrics into the corrugations before the strips are engaged, said strips being respectively formed with recesses which become mutually aligned when the strips are engaged, the aligned recesses forming a needle path through the corrugations for receiving a threaded needle for sewing the lining and necktie fabrics between the engaged strips.

4. Sewing mechanism according to claim 3 and wherein said rods are connected as two units on either side of the strips, each of said units being pivotable so as to swing the rods as a unit into the corrugations of each strip.

5. Sewing mechanism according to claim 4 and including means for slidably withdrawing said rods from within said corrugations.

6. Sewing mechanism comprising a pair of corrugated and complementary strips for crimping a length of fabric, the corrugations of one strip being adapted to engage the corrugations of the other strip, means for urging the fabric into the corrugations before the strips are engaged, said strips being respectively formed with recesses which become mutually aligned when the strips are engaged, the aligned recesses forming a needle path, and needle means for traversing said needle path so as to sew the fabric maintained between the engaged strips, a pair of platforms which are pivotally interconnected, said strips being supported on the respective faces of the platforms and disposed so as to become engaged when the platforms are relatively pivoted so as to be brought into substantial planar contact with each other, and a series of fabric impaling needles operating through openings in the strips for holding the fabric thereto before said platforms are pivoted to effect engagement of the strips.

7. Sewing mechanism comprising a pair of corrugated and complementary strips for crimping a length of fabric, said strips being adapted to engage each other by their corrugations and being respectively formed with recesses which become mutually aligned when the strips are engaged, the aligned recesses forming a needle path through the corrugations for receiving a threaded needle so as to sew the fabric maintained between the engaged strips, at least one of said strips including an elongated end section having its axis inclined relative to the axis of the adjacent strip section.

8. Sewing mechanism according to claim 7 and wherein the other strip end section is likewise elongated and has its axis inclined relative to the adjacent, center section, the inclinations of both said end sections being toward each other, said recesses assuming a path substantially in alignment with the axes of the three strip sections.

9. Sewing machine according to claim 8 wherein both said strip end sections are substantially trapezoidal in shape.

10. Sewing mechanism comprising a pair of normally horizontally aligned platforms, a cor-

rugated strip on each of said platforms, both of said strips being adapted to simultaneously support the respective longitudinal edge portions of an elongated necktie fabric when said fabric is laid thereover in the normal position of the platforms, the corrugations of the respective strips being complementary and engageable so that said fabric may be retained in crimped form between said strips when engaged, one of said platforms being stationary, the other platform being movable so as to bring said strips into engagement.

11. Sewing mechanism comprising a pair of corrugated and complementary strips for crimping a length of fabric, the corrugations of said strips being engageable so as to maintain said length of fabric in crimped form between them, a pair of platforms on which said strips are respectively supported, said strips being respectively formed with recesses which become substantially aligned when the corrugated strips are engaged, the substantially aligned recesses forming a needle path through the corrugations for receiving a threaded needle so as to sew the fabric maintained between the engaged strips, at least a portion of each of said strips being movable laterally on its platform.

12. Sewing mechanism according to claim 11 and wherein each strip comprises three elongated sections, each of said sections being independently laterally movable on the platform.

13. Sewing mechanism according to claim 12 and wherein said platforms are pivotally connected together, pivotal relative motion of said platforms being effective in bringing said strips into engagement.

14. Sewing mechanism according to claim 13 and including a series of fabric impaling needles operating through slots in at least one of said platforms and strips for impaling the fabric before pivotal action of said platforms is commenced in engaging said strips.

15. Sewing mechanism according to claim 14 and including two groups of connected rods adjacent the respective strips, each of said groups of rods being pivotable so as to swing the rods as a unit into the corrugations of each strip, a rack for slidably supporting each of said groups of rods, each group being slidable on said rack so that the rods may be withdrawn from within said corrugations after the fabric has been sewn.

16. Sewing mechanism according to claim 15 and including a plate for supporting a series of fabric impaling needles in substantial alignment, and cam means for actuating said plate in a vertical direction so as to cause said needles to ride up or down in the slots of the strips.

17. Sewing mechanism comprising a pair of corrugated and complementary strips for crimping a length of elongated fabric, said strips being normally horizontally aligned and adapted to simultaneously support the respective longitudinal edge portions of said length of fabric, the corrugations of one strip being such as to form narrow peaks and wider valleys on the face thereof, the other strip having wider peaks and narrower valleys, a series of recesses being formed across the peaks of both strips, said peaks becoming substantially aligned when the corrugations of one strip are brought into engagement with the corrugations of the other strip, the aligned recesses forming a needle path for sewing fabric maintained between the engaged strips.

18. A method of sewing the edges of a tie fabric which comprises separately corrugating the edges

thereof in complementary arrangement, bringing the respective edges together so as to cause the corrugations to become engaged and sewing through all the corrugations by a slip stitch through adjacent crests of the corrugated fabric for sewing the edges together.

19. A method of sewing the edges of a tie fabric which comprises separately corrugating the edges thereof in complementary arrangement and while the fabric is disposed on a support, impaling inner portions of said tie fabric so as to fix the fabric in position relative to said support, bringing the respective edges together so as to cause the corrugations to become engaged while the fabric is impaled and thereafter sewing through all the corrugations by a slip stitch through adjacent crests of the corrugated fabric for sewing the edges of the fabric together.

20. A method of sewing the edges of an elongated tie fabric which comprises separately crimping the edges thereof, folding the tie fabric along its longitudinal axis so that crimped edges are caused to be superimposed and sewing through said crimped edges by a slip stitch through adjacent crests of the crimped fabric for sewing the edges together.

21. A method of sewing a necktie lining to a tie fabric which comprises superimposing one edge of the tie fabric across a central longitudinal line of the lining, crimping said one edge and the necktie lining together and crimping the other edge of the tie fabric, and thereafter folding said tie fabric along its longitudinal axis so as to bring its edges into crimped engagement and finally sewing along said edges by a slip stitch through adjacent crests of the crimped edges for sewing the edges together.

22. A method of sewing a necktie lining to a tie fabric which comprises superimposing one edge of the tie fabric across a central longitudinal line of the lining and while the fabric and lining are disposed on a support, crimping said one edge and the necktie lining together and crimping the other edge of the tie fabric, impaling portions of said tie fabric against said support so as to fix it in position relative thereto, folding said tie fabric along its longitudinal axis so as to bring its edges into crimped engagement and finally sewing along said edges by a slip stitch through adjacent crests of the crimped fabric for sewing the edges together.

23. A method according to claim 22 and including the steps of holding down the necktie lining and tie fabric before impaling said inner portions of said tie fabric.

24. A method of sewing the edges of an elongated tie fabric which comprises folding the tie fabric along its longitudinal axis while superimposing and crimping the edges thereof and thereafter sewing the crimped edges by a slip stitch through adjacent crests of the crimped edges for sewing the edges together.

25. A method according to claim 24 and including the step of first impaling portions of said tie fabric against a support therefor before folding it along its longitudinal axis.

26. Sewing mechanism comprising a pair of corrugated, elongated and complementary strips for crimping a length of fabric, said strips being respectively formed with recesses which become

mutually aligned when the corrugations of the respective strips are engaged, the aligned recesses forming a needle path through the corrugations for receiving a threaded needle so as to sew the fabric maintained between the engaged strips, at least the top portion of said strips being movable laterally, each of said strips being formed with needle holes therethrough, a series of needles arranged for movement within said needle holes so as to impale a length of fabric disposed over said strips, and holding bars for pressing the fabric down during the impaling action, the holding bars being formed with openings for receiving the impaling needles as they emerge from the needle holes of the strips, said holding bars being shiftable so that said openings and the needle holes may be aligned.

27. Sewing mechanism comprising a pair of corrugated, elongated and complementary strips for crimping the edges of a length of fabric, the corrugations of said strips being engageable so as to maintain said length of fabric between them with the fabric edges being crimped, each of said strips having its top portion formed with a plurality of rows of recesses which become aligned with the respective rows of recesses of the other strip when the strips are engaged, the aligned rows of recesses forming a plurality of selectable paths through the corrugations for receiving a threaded needle so as to sew the fabric edges maintained between the engaged strips.

28. A method of sewing the edges of an elongated tie fabric to an elongated tie lining which comprises superimposing one longitudinal edge of the tie fabric over the lining, folding the tie fabric along its longitudinal axis so as to bring its edges together and in superimposed relationship, crimping said edges and lining and thereafter sewing the crimped edges and lining together.

29. Sewing mechanism comprising a pair of corrugated and complementary strips for crimping a length of fabric, the corrugation of one strip being adapted to engage the corrugation of the other strip, said strips being respectively formed with recesses which become mutually aligned when the strips are engaged, the aligned recesses forming a needle path, and needle means for traversing said needle path so as to sew the fabric maintained between the engaged strips, a pair of platforms which are pivotally interconnected, said strips being supported on the respective faces of the platforms and disposed so as to become engaged when the platforms are relatively pivoted so as to be brought into substantial planar contact with each other, and a series of fabric impaling needles operating through openings in the strips for holding the fabric thereto before said platforms are pivoted to effect engagement of the strips.
